UNITED STATES PATENT OFFICE.

ALEXANDER E. BROWN, OF CLEVELAND, OHIO.

HOISTING AND CONVEYING MACHINE.

SPECIFICATION forming part of Letters Patent No. 390,560, dated October 2, 1888.

Application filed March 15, 1887. Serial No. 231,021. (No model.)

To all whom it may concern:

Be it known that I, ALEXANDER E. BROWN, of Cleveland, in the county of Cuyahoga and State of Ohio, have invented certain new and useful Improvements in Hoisting and Conveying Machines; and I do hereby declare that the following is a full, clear, and exact description thereof, reference being had to the accompanying drawings, making part of this application.

My invention relates to certain new and useful improvements in hoisting and conveying machines, some or all of which improvements, though specially adapted for use in an apparatus designed for hoisting and conveying the material in digging ditches for sewers, &c., may be used in connection with hoisting and conveying apparatus for other purposes.

The machine or apparatus made the subject of this application belongs to that well-known type in which there is a carriage that travels upon some sort of elevated tramway or track, the said carriage being moved in both directions by an endless cable, and in which there is also another cable, generally designated as the "hoist-rope," that is secured to a fixture at one end and has its other end wound upon the usual drum of the hoisting-engine located in the engine-house of the structure.

My present invention consists in certain novel features of structure in this type of machine, which features will be hereinafter more fully explained, and will be most particularly pointed out and defined in the claims of this specification.

To enable those skilled in the art to which my invention relates to make and use the same, I will now proceed to more fully describe the several features of my improvement, referring by letters of reference to the accompanying drawings, which form part of this specification, and in which I have shown my invention carried out in that form which is the best known to me, and in which I have so far successfully practiced it.

In the drawings, Figure 1 is a perspective view of an elevated single-track tramway and the appliances thereof, such as I have already practically used (in the hoisting and conveying of material in the construction of sewers) and embracing the several features of my present invention. Fig. 2 is a view

showing detached or separately, but mounted on the tramway, one of the traveling carriages or machine and the load-sustaining sheave-block in side view or elevation. Fig. 3 is an end or edge view of the parts shown at Fig. 2. Fig. 4 is a reverse side view of machine shown at Fig. 2. Fig. 5 is a sectional detail.

In the several figures the same parts will be found designated by the same letters of reference.

The structure upon which are supported and on which travel the conveying-carriages of the apparatus is composed, preferably, of a series of A-frames, A, from the apices of which is suspended a single continuous track-beam, B, by means of metallic suspenders or supporting devices C. At one end of the structure, near the terminus D of the track-beam, is properly secured to the frame-work the usual anchorage, to which is attached the fixed end of the hoist-rope y in the customary manner, and which also carries, in the usual manner, a sheave or pulley, over which travels the endless cable E, to which are properly secured at any desired intervals the carriages or machines F, and of course at the opposite end of the tramway (although not shown in the drawings) are the usual engines and drums and their connections, by means of which the endless carriage-driving cable is caused to travel in the desired manner, and by which also the hoist-rope is taken up and let out, in a manner well known, for the purpose of hoisting and lowering the buckets or tubs I, which are connected in the usual manner with the depending hook of the sheave-block J. These sheave-blocks are constructed substantially according to the most approved plan, but have combined with them and the machine or carriage suitable rubber or other elastic cushions, C, arranged as shown, so that whenever the sheave-block is elevated or pulled up (to engage with the detaining devices of the machine) said block will cushion at its top edge against the elastic stops C, thus preventing the usual jar and consequent sudden strain or shock upon the parts of the apparatus experienced in the use of machines as made previous to my invention.

The elastic stop or cushion C, I have made in the form of a short rubber tube, which I

have simply applied to the shaft or arbor *e* of the depending load-hook *d*, said rubber tube having a bore equal to the size of the arbor *e* and an external circumference sufficient, as seen by the dotted circle at Figs. 2 and 4, to leave the requisite space between the lower-most point in the periphery of *C* and the highest point in the upper edge of the sheave-block *J* to permit the unseating of the latter from the hooks *d*; but of course the form of and the mode of securing in place the cushion *C* may be varied from what I have shown, it being essential only that said cushion be securely held in place between the metallic plates of the machine or trolley *F* at the proper locality to act as a bumper for the sheave-block *J* whenever the latter may be suddenly run up slightly above the point necessary to seat it in the load-sustaining hooks *d*.
 20 *d d* are the sustaining-hooks, a pair of which is supplied to each of the carriages or machines, the said hooks being arranged at either side of the machine and being secured at their upper ends to a stud or spindle, *e*, which revolves in a suitable bearing-box near the upper part of the machine, and having their lower ends made hook-shaped, and adapted to pass beneath and support the laterally-projecting ends of the sheave-spindle or sheave-block hubs *t* at certain times, when it may be desired to traverse the load-carrying machines without undue or material friction or strain upon the hoist-rope, which latter, of course, always passes partially around the two rope-wheels *W* of the carriage and the sheave (shown by dotted circle at Fig. 2) of the sheave-block *J*.
 25

Each of the carriages is provided, as shown, with clamping devices *f*, which are adapted at their upper parts to grip the traversing rope or cable *E*, for the purpose of fastening each of the said carriages to said traversing cable at any point at which it may be desired to make the connection, for the purpose of causing the said carriage (and its depending bucket) to traverse through any desired portion of the length of the entire "run" of the conveying-machines. By the use of these clamping-jaws *f*, (which are pivoted at 1 and provided with securing-bolts at 2,) or by other suitable means for thus securing the carriages *F* to the traversing rope *E* at any desired point, I am enabled in the use of the apparatus to give any one or more of the machines a limited run back and forth over any specified portion of the excavation or work where alone it may be desired to operate the buckets. This is of advantage in doing certain kinds of work, especially in the digging of sewer-ditches, &c.
 30

35 60 Each of the carriages is provided, as shown, with anti-friction safety-rollers *i i*, which are arranged in the carriages so as to come slightly below the lower edge of the track-beam *B*, and which serve in case of the presence of any obstruction on the track to prevent the track-wheels of the carriage from rising far enough to become derailed or thrown

from the track. The carriages are also provided with safety or guard irons or hooks *q q*, arranged, as shown, to clear but hooking over the track to such an extent that the guard-rollers *i i* will not allow the same to ever lift above the top of the rail. In case the flanges of the track-wheels break, the weight of the machine will be held by these safety-irons *q* dropping onto the rails, the hook ends thereof preventing the machine from swinging side-wise, thus preventing any possibility of the carriage falling from the track. These safety-rollers in conjunction with the safety or guard irons above the track, I consider of much importance in the practical running of the machine.
 40

In a traveling carriage of the kind shown and described mounted to travel upon a single track, and being suspended from the track-wheels, as shown, so that the depending sides or portions of the carriage-frame *F* have to run in close proximity to one of the vertical sides of the track-beam *B*, it frequently happens that by the swaying of the load, or from other causes, such portions of the carriage-frame are liable to come into contact with and rub against said vertical side of the track-beam, thus causing undue friction with a commensurate waste of the power of the driving machinery and more or less injurious wear to the parts of the apparatus. To overcome this difficulty or objection in the type of machine shown, I have provided those portions of the carriage frame which are apt to come in contact with the vertical side of the track-beam with anti-friction rollers or wheels *m*, which are designed to ride against or roll on the vertical surface of the beam *B* whenever the depending carriage may be swayed toward the beam, and to avoid all rubbing between the parts, and thus prevent the usual undue wear thereof and all wastage of power.
 45

50 The load-sustaining hooks *d d* may be arranged in an opposite manner with reference to any two adjacent carriages in the whole contrivance, as shown by the relative positions of the hooks at Figs. 2 and 4, so that, when desired, a pair of machines that are being used simultaneously can have their load-sustaining hooks *d* manipulated by a single attendant, either separately or simultaneously, at pleasure, by means simply of suitable cords or rods attached at their upper ends to the hooks of the two machines, as shown at *o o*, and connected at their lower ends to a common loop, *P*, in such manner that by pulling upon a rod or rope, *u*, attached to said loop *P*, either in one direction or another laterally either one or the other of the hooks may be manipulated, and so that by pulling vertically down upon said rod or rope *u* both the said hooks may be operated at once. The arrows at Figs. 2 and 4 illustrate the different directions in which the attendant may pull the cord *u*, depending from the ring *P*, for the purpose of manipulating either one or both of the load-sustaining hooks *d* at pleasure. This arrangement

ment of the hooks *d* in a pair of the traveling carriages *F*, and this means for manipulating said hooks render it exceedingly convenient and expeditious for an attendant to manage 5 the machines in pairs with reference to the lowering and discharging of the buckets or tubs singly or in pairs, as may be desired. These sustaining-hooks *d* co-operate with the hoist-blocks and their hoist-rope in such manner that while the loads can be raised and lowered by the engineer no bucket can be lowered without the co-operation of the attendant on the ground, and at the same time the lowering of the bucket by the attendant 10 cannot be effected except with the knowledge and co-operation of the engineer, who has to manipulate the hoist-rope in such manner as to relieve the sustaining-hooks *d* from the gravity of the load before the attendant can 15 manipulate the hooks, (in the manner just above explained,) and thus permit the descent of the loaded bucket; but this feature need not be further explained herein, as it constitutes no part of the subject-matter of invention sought to be covered by this application. 20 Having now so fully explained the several novel features of construction of my improved apparatus that those skilled in the art can make and use a hoisting and conveying machine embracing either one or all of said features in either the precise form or forms in which I have used them or in some other adapted to answer the same purpose, and wishing it to be understood that the details of construction with reference to any or all of the 25 said novel features may be more or less varied

without departing from the spirit of my invention, what I claim as new, and desire to secure by Letters Patent, is—

1. The combination, with the carriage *F* and the sheave block *J*, of a suitable cushion or buffer, *C*, operating, substantially as specified, to receive and take up any sudden shock or momentum which might otherwise injuriously jar the apparatus upon any sudden and too great elevation of the sheave-block. 40

2. In combination with a pair of traveling carriages, *F*, the sustaining-hooks *d*, arranged as specified, and cords or rods which are connected to said hooks and are connected together at their lower ends, whereby with the use of some suitable implement an attendant may manipulate the hooks *d* of the carriages either separately or simultaneously, in the manner and for the purposes hereinbefore 50 specified. 55

3. In a hoisting and conveying machine of that type which embraces a tramway of some sort for the traveling carriages, a hoist-rope anchored to one end of the tramway, an endless carriage-driving rope, and the clamps or securing devices *f* on the carriages *F*, which serve to clamp the carriage to the traversing or driving cable at any desired points, in substantially the manner and for the purposes explained. 60 65

In witness whereof I have hereunto set my hand this 31st day of August, 1886.

ALEXANDER E. BROWN.

In presence of—

E. T. SCOVILL,
CHAS. W. KELLY.
